UNITED STATES PATENT OFFICE

2,573,372

FLORAL DISPLAY STAND

Karl F. Wagler, Chicago, Ill.

Application March 29, 1949, Serial No. 84,139

2 Claims. (Cl. 248—27.8)

1

This invention relates to display stands and more particularly to display stands as used for supporting floral arrangements and pieces including vases, wreaths and other forms of displays.

The principal objects of the invention is the provision of a floral display stand and removable vase portion.

A further object of the invention is the provision of a combination floral display stand and vase removably secured to one another.

A still further object of the invention is the provision of a display stand and vase arrangement having connecting means enabling the vase to be removed from the stand and positioned in a self-supporting manner in the earth.

The display stand shown and described herein comprises a device primarily intended for displaying floral arrangements such as vases, wreaths and floral displays of other forms as commonly used in connection with funerals and the like and wherein the various display stands of different heights may be employed for receiving and holding the floral pieces and arrangements.

The principal novelty in the floral display stand disclosed herein is in the combination therewith of a removable vase or other floral piece supporting member which incorporates means for rendering the vase capable of standing vertically on the earth at such time as, for example, the vase portion of the device is removed to the cemetery.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a side elevation of the floral display stand and vase.

Figure 2 is an enlarged horizontal section taken on line 2—2 of Figure 1.

Figure 3 is a side elevation of a modified form of floral display stand and a flower holding member.

Figure 4 is a view of the vase portion of the floral display stand and vase shown in Figure 1.

Figure 5 is a plan view of a modified form of flower supporting member.

2

By referring to the drawings and Figures 1 and 2 in particular it will be seen that the floral display stand and vase combination comprises a stand portion formed of a plurality of vertical support members 10 (for example, four in number) radially spaced with respect to one another and secured to one another by circular wire shapes 11. The circular wire shapes 11 are of varying diameter, the largest being located adjacent the bottom ends of the support members 10 and the smallest being located adjacent the upper ends thereof. The lowermost ends of the support members 11 are preferably formed in upturned loops 12 and each of the uppermost wire shapes 11 is provided with a plurality of secondary loops 13 radially spaced thereabout, as best shown in Figure 2 of the drawings. The two rows of radially spaced loops 13 are relatively small and located in substantial but not accurate vertical alignment with one another. A vase 14 has a plurality of depending prongs 15 secured to the bottom thereof, each of which is adapted to be positioned through two of the radially spaced loops 13. The floral display stand and vase will thus be seen to comprise the combination of the stand portion formed of the vertical support members 10 and the vase 14 with the prongs 15 thereof adapted to be detachably engaged in the loops 13 of the stand.

The general tapering shape of the stand portion of the device and the different diameters of the two rings 11—11 will be seen to secure the prongs 15 in the loops 13—13 by distorting the same and hence holding the vase 14 in relatively secure engagement with the stand portion of the device so that it will not be accidentally separated therefrom. The composite device may be used in positioning and supporting floral displays, the floral container being positioned directly in the vase 14 or the flowers themselves may be positioned directly therein. In either event, at such time as it is desired to move the floral displays from the initial point of display to a remote location, the vase 14 may be detached from the stand portion and will then form a vase capable of supporting itself upright when positioned on the earth or sod as, for example, in a cemetery, as best shown in Figure 4 of the drawings.

The particular formation of the floral display device will be seen to make possible the display of various types of floral arrangements. By referring to Figure 3 of the drawings a modified form of the device may be seen to be formed

of twisted metal strip, the vertically standing legs thereof being indicated by the numeral 16 and provided at its upper end with a modified means of connecting a flower supporting member. The modified means comprises an annular band 17 of suitable material secured to the upper ends of the legs 16 and slit at intervals in spaced pairs to form substantially vertically aligned partial loops 18 which will receive and retain a plurality of depending prongs 19 secured to a framework 20 on which a floral arrangement may be positioned.

It will occur to those skilled in the art that modifications of the framework 20 may be made to hold different types of floral arrangements and pieces and by referring to Figure 5 of the drawings an arrangement may be seen for supporting a wreath. A wreath supporting frame 21 is provided with a plurality of depending prongs 22 which are adapted to register with the support stands shown in Figures 1 and 3 of the drawings.

It will thus be seen that a simple and inexpensively constructed floral display stand has been disclosed which may be formed of readily available materials and will provide attractive and practical means of supporting floral displays with the desirable feature of enabling the vase or floral supporting portion of the device to be separated from the standard portion and removed to a remote location. It will occur to those skilled in the art that the vase portion 14 or the framework 20 or wreath support member 21, as disclosed herein, may be and preferably are inexpensively formed so that they may be used once and then discarded. The standard portion of the device may obviously be retained and reused as desired.

Having thus described my invention, what I claim is:

- 5 1. A floral display device comprising in combination a standard and a flower holding member, two rows of radially spaced rings on said standard the flower holding member having several radially spaced prongs detachably engaging the said rows of rings on said standard for normally securing the said flower holding member thereto.
- 15 2. A floral display device comprising a standard formed of a plurality of vertically standing inclined support members, ring-like members spacing the said support members, radially spaced loops formed on at least two of the said ring-like members adjacent the uppermost end of the standard and a flower holder having a plurality of radially spaced depending prongs positioned theron for detachable engagement with the said radially spaced loops.
